METHOD AND DEVICE FOR LOADING WIRE COILS ON A FRAME
Josef Baumann, Schaffhausen, Switzerland, assignor, by mesne assignments, to The Wheelabrator Corporation, Mishawaka, Ind., a corporation of Delaware
Filed Oct. 23, 1962, Ser. No. 232,434
10 Claims. (Cl. 214—1)

This invention relates to the processing of bundles of wire and it relates more particularly to a method and means for opening a wire bundle to expose the surfaces of the wire for surface treatment, as by abrasive or cleaning particles or compositions centrifugally thrown or otherwise applied to the surface.

This invention will be described with reference to the treatment of the surfaces of the wire with centrifugally thrown abrasive or cleaning particles for the removal of scale and the like prior to the processing of the wire in various metallurgical operations. It will be understood, however, that the concepts of this invention will have application also to other methods or means for treatment of the surfaces of the wire.

For such purpose, the wire is usually supplied in the form of substantially endless lengths wound into a compact bundle whereby it becomes difficult for the abrasive particles or other surface treating material to penetrate into the interior of the bundle. As a result, the surface portions of the wire in the interior of the bundle are not properly exposed to the treating material.

It is an object of this invention to provide a new and novel means and method for opening a wire bundle for full exposure of the surfaces of the wire to such surface treating materials or other material for surface treatment and then to reform the wire after surface treatment into a bundle.

These and other objects and advantages of this invention will hereinafter appear and for purposes of illustration, but not of limitation, an embodiment of the invention is shown in the accompanying drawings in which—

FIG. 1 is a schematic elevational view partially in section of the arrangement of the elements embodying the features of this invention with the elements in position prior to opening the bundle.

FIG. 2 is a schematic sectional elevational view of the structure shown in FIG. 1 with the elements in position for opening the wire bundle; and

FIG. 3 is a schematic sectional elevational view of the structure shown in FIGS. 1 and 2 with the elements in position to secure the wire bundle to the frame.

Referring now to FIG. 1 of the drawing, a loading platform 10 rests upon a supporting surface 12 in position to be located in vertical alignment with a loading pit 14. An annular disk 16 is removably secured, as by clamping means (not shown) or by bolt and nut means 18 to the top side of the platform 10 with the central opening 20 in the annular disk plate being vertically aligned with the pit 14 and dimensioned to be slightly greater than the cross-section of the pit.

Shiftable vertically in the direction toward and away from the platform is a frame plate 22 having a plurality (at least 3) of frame rods 24 extending downwardly in parallel relationship from the under side of the frame plate 22 in a substantially equally spaced apart arrangement about a circular pattern having a dimension less than the circular cross-section or other pattern of circular or polygonal shape of the pit 14 thereby to enable the depending frame rods to be displaced through the opening 20 of the disk plate 16 and into and out of the pit 14. The frame rods 24 are preferably interconnected by cross brace or bridging members 26 to provide stiffness or rigidity

2

and for maintaining the desired spaced relationship between the rods.

Both the frame plate 22 and the disk plate 16 are provided with means, such as clamping means or hook means for removably securing the opposite ends of the wire in the wire bundle 28. Such wire clamping means are preferably provided respectively on the bottom side of the frame plate 22 and the top side of the disk plate 16.

Various means may be employed for raising and lowering the frame plate 22 and the attached rods 24 between raised and lowered positions. In the illustrated modification, one such means comprises a bale 30 extending upwardly from the top side of the frame plate 22 and which is adapted releasably to be engaged by a hook member 32 on the end of a pulley 34 connected by cables 36 to a hoist 38. The hoist may form a part of a cable car 40 having wheels 42 movable on tracks 44 for displacement of the cable car, hoist, and the frame plate from registry with the pit 14 to other processing stations for wire treatment or for transportation of the wire bundle from a source of supply to the opening means described or for delivery of the bundle of processed wire to storage.

Having described the basic structure of the elements, illustration will now be made of the use thereof in handling a wire bundle for processing.

A loading disk 16 is clamped onto the stand 10 and a wire bundle 28 is placed onto the top side of the clamped disk plate 16.

The trolley car 40 is positioned vertically to align the frame plate 22 and the depending rods 24 with the loading pit 14 and the frame plate is then lowered to project the frame rods downwardly through the disk plate 16 and the wire bundle 28 and into the pit 14 until the bottom side of the frame plate 22 closely approaches the wire bundle 28 or preferably comes substantially into engagement with the top surface thereof. One end of the wire bundle is fixed at 46 to the underside of the frame plate 22 while the other end of the wire bundle is fixed to the disk plate. Thereafter the wire bundle is freed of binding wire or other binding members to release the coils and the hoist is operated to raise the frame plate in the direction away from the disk plate. This operates to spread the coils of the wire in the bundle about the spacing frame rods 24 to the position shown in FIG. 2. When displaced by the desired amount to achieve the intended spread between the coils of wire in the bundle, the disk plate 16 is removably secured to the adjacent portions of the frame rods 24 thereby to maintain the disk plate and the frame plate in the predetermined spaced relationship with the wire coil spread therebetween about the intervening lengths of the frame rods 24.

In this arrangement, the hoist can raise the frame plate with the rods attached thereto and the disk plate carried thereon with the coils of the wire bundle spread about the spaced rods between the frame plate and the disk plate. When displaced from the pit and from the stand, the assembly can be moved to any treating station. The assembly can be exposed to a blast area of centrifugally thrown finely divided abrasive or other material for surface treatment, for cleaning, etc., with all surfaces of the wire accessible for such surface treatment.

The described sequence of steps can be reversed to return the treated wire to form the compact bundle, i.e., the assembly is returned into vertical alignment with the pit and the stand 10; the assembly is then lowered by the hoist into the pit until the disk plate 22 again comes to rest on the stand. Thereafter, the disk plate is disengaged from the frame rods so that the rods are free for movement relative to the disk plate into the pit whereby the coils of wire are returned from their spread position to reform the compact wire bundle. When the frame

plate returns to starting position, the reformed bundle can be tied and then the ends of the wire bundle can be disengaged from the respective disk plate and frame plate to free the reformed wire bundle for removal from the stand when the rods are raised from within the wire bundle.

The separation of the frame and disk plates for spreading the coils of wire should be conducted in a manner which avoids deformation of the wire to a point beyond its elastic limit. This enables the reformation of the bundle, as previously described, when the processing has been completed. The amount of spread can be varied depending upon the length, the size or the cross-section of the wire or the diameter of the wire ring or bundle. The spacing can be varied by adjustment in the amount of displacement of the frame plate relative to the disk plate. For this purpose, means are provided for attachment of the disk plate to the frame plate in its various positions of adjustment.

By way of modification, the device described can embody a traction means within the pit 14 for operative engagement with the frame rods for positive displacement of the frame rods into the pit. This modification is especially adapted for reforming the wire bundle upon completion of the wire processing step or steps.

By way of further modification, it will be understood that the elements described may be arranged for relative movement in a horizontal direction instead of vertical as by providing for horizontal displacement of the frame plate and rods into and out of the wire bundle properly supported on a vertically disposed platform. For such purpose, the elements will be arranged in somewhat the same fashion as shown in FIG. 1 but turned to an angle of about 90° to the vertical. Under such circumstances a pit will not be necessary beyond the stand.

This method and apparatus can be used to advantage with stiff wires. Wires of different cross-sections such as circular, square, rectangular or of other polygonal shape may be spread in accordance with the practice of this invention. While the description refers primarily to the spreading of bundles of wire, it will be understood that the concepts described will have application also for spreading bundles of metal strip or bands.

It will be understood that changes may be made in the details of construction, arrangement and operation without departing from the spirit of the invention, especially as defined in the following claims.

I claim:

1. The method of spreading a bundle of continuous coils of metal for surface treatment comprising the steps of positioning the bundle on a stationary platform, displacing an elongate frame dimensioned to be less than the opening through the bundle from one side of the bundle opposite the platform and through the opening until a frame plate on the one side of the frame is positioned adjacent the side of the bundle opposite the platform to locate the bundle between the platform and the frame plate, securing one end of the coils in the bundle to the platform and securing the other end of the coils in the bundle to the frame plate, displacing the frame in the direction away from the platform to spread the coils over the frame, and connecting the one end of the coils to the adjacent portion of the frame whereby the coils are secured in their spread relationship on the frame, and removing the frame with the coils spread thereon for treatment.

2. The method of spreading a bundle of continuous coils of metal for surface treatment comprising mounting the bundle on a disc plate having an opening therethrough corresponding to the opening of the coil bundle, releasably securing the disc plate to a stationary platform having an opening corresponding to the opening in the disk

plate, securing one end of the coils in the bundle to the disc plate, displacing an elongate frame lengthwise through the opening of the coil bundle, disc plate and platform from the direction opposite the disc plate until a frame plate on the frame is positioned adjacent the side of the bundle opposite the disc plate, securing the other end of the coils in the bundle to the frame plate, displacing the frame plate in the direction away from the disc plate to spread the coils of the bundle over the frame, securing the disc plate to an adjacent portion of the frame, and releasing the disc plate from the platform whereby the spread coils of the bundle are secured in their spread relationship on the frame.

3. Apparatus for mounting a bundle of continuous coils of metal in spread relationship for surface treatment comprising a stationary platform having an opening therethrough corresponding to the opening through the bundle, a disc plate having an opening therethrough corresponding to the opening in the bundle, means for releasably securing the disc plate onto the platform, an elongated frame dimensioned to be slightly less in crosswise dimension than the opening through the bundle, disc plate and platform to enable displacement therethrough, a frame plate on the end portion of the frame means for securing one end of the wire coils in the bundle to the frame plate, other means spaced lengthwise from said first means for securing the other end of the wire coils in the bundle to the disc plate, and means for displacement of the frame and frame plate lengthwise in the direction toward and away from the disc plate and platform.

4. Apparatus for mounting a bundle of continuous coils of metal in spread relationship for surface treatment comprising a stationary platform having an opening therethrough corresponding to the opening through the bundle, a disc plate having an opening therethrough corresponding to the opening in the bundle, means for releasably securing the disc plate onto the platform, an elongate frame dimensioned to be slightly less in crosswise dimension than the opening through the bundle a frame plate on the end of the frame, means for securing one end of the wire coils in the bundle to the frame plate, means for securing the other end of the wire coils in the bundle to the disc plate means for releasably securing the disc plate to the frame and means for displacement of the frame and frame plate lengthwise in the direction toward and away from the disc plate and platform.

5. Apparatus as claimed in claim 4 in which the platform is horizontally disposed and overlies a well dimensioned to receive a substantial length of the frame.

6. Apparatus as claimed in claim 4 in which the opening in the platform is dimensioned to be less than the other diameter of the bundle but more than the inner diameter of the bundle.

7. Apparatus as claimed in claim 4 in which the opening in the disc plate is dimensioned to be less than the outer diameter of the bundle but more than the inner diameter of the bundle.

8. Apparatus as claimed in claim 4 in which the frame comprises a plurality of elongate interconnected rods arranged in a circular path having a diameter slightly less than the diameter of the opening through the bundle.

9. Apparatus as claimed in claim 4 in which the frame plate is an integral part of the frame and dimensioned to be greater in the crosswise directions than the inner diameter of the bundle.

10. Apparatus as claimed in claim 4 in which the means for displacement of the frame and frame plate comprises a hoist mounted for vertical lifting movement and crosswise transport movement.
